UNITED STATES PATENT OFFICE.

ADELIA G. SHRAUGER, OF ODANAH, WISCONSIN.

PUMP-DRAIN.

1,334,408.

Specification of Letters Patent. Patented Mar. 23, 1920.

Application filed September 25, 1919. Serial No. 326,340.

To all whom it may concern:

Be it known that I, ADELIA G. SHRAUGER, a citizen of the United States, residing at Odanah, in the county of Ashland and State of Wisconsin, have invented certain new and useful Improvements in Pump-Drains, of which the following is a specification.

My invention relates to new and useful improvements in a pump attachment and more particularly to a drain for the pump pipe or cylinder.

The invention has for its principal object the construction of a drain which may be easily connected to the pump pipe beneath the platform for draining the pipe of water so that it will not freeze.

A further object of the invention resides in the provision of a valve adapted for closing the drain when pumping and adapted to be raised to open the drain after pumping so that the water will drain from the pipe.

A further object resides in the provision of novel means for connecting the drain to the pump pipe as well as means for operating the valve and holding it in both its open and closed positions.

With these and other objects in view my invention consists in the novel details of construction and arrangement of parts which will be more clearly understood from the following specification and drawings in which:—

Figure 1 is a side elevation.

Fig. 2 is a horizontal section on the line 2—2 of Fig. 3, and

Fig. 3 is a transverse vertical section on the line 3—3 of Fig. 2.

In the drawings the numeral 1 indicates the platform over the well and 2 indicates the pump pipe or cylinder which extends through the platform down into the well. It is a well known fact that in winter it is desired to drain the pump pipe, below the platform 1, so that the water will not freeze in the pipe and break the same. It is for this purpose that my invention is provided.

My attachment comprises a block 3 the inner face of which is concave as more clearly illustrated in Fig. 2 of the drawings so as to conform to the curvature of the pipe. A transversely extending opening or bore 4 is formed in the block 3, intermediate the ends thereof, and this bore or opening extends from the concave face of the block to a point

adjacent the opposite side. This bore or opening 4 is adapted to register with an opening 5 formed in the pipe 2. A vertical opening 6 is also formed in the block 3 and extends from the top thereof and communicates with the opening or bore 4 as more particularly illustrated in Fig. 3 of the drawings. A recess is formed in the concave face of the block 3, around the end of the opening or bore 4, and is adapted to receive a rubber gasket 7 so that a tight fit will be secured around the opening 5.

A flange 8 is formed on each side of the block, adjacent the rear face thereof, and an extension 9 extends upwardly from the block as is more particularly illustrated in Fig. 1 of the drawings. Posts 10 are secured to the top of the block 3, adjacent the concave face thereof, and support a plate 11 at the upper end of the extension 9. If desired the plate 11 might be connected to the extension 9 in any desired manner. The forward end of the plate 11 is concave so as to conform to the curvature of the pipe which it engages. An opening is formed in the plate 11 for a purpose to be later described.

U-shaped clamps or rods 12 extend around the pipe 2 and the end pass through the flanges 8 formed on the block 3. Nuts 13 are received on the ends of the rods for securely holding them in position. A similar U-shaped clamp rod 14 extends around the pipe 2 and the ends pass through the extension 9 adjacent the upper end thereof. The arms of this U-shaped clamp 14 engage the side of the plate 11. Nuts 15 are received upon the ends of the rods 14 for securing them to the extension 9.

A tube 16 is secured to the top of the plate 11, around the opening therein, and this tube extends through the platform 1 as is clearly illustrated in Fig. 1 of the drawings. A tapered valve 17 is adapted to be received in the vertical opening 6 of the block 3 and a reduced extension 18 is formed on the top of the valve and has an eye 19 secured thereto. The tapered valve 17 is preferably of such a length as to extend entirely through the opening 6 when in position. A wire 20 is secured to the eye 19 and extends upwardly through the opening in the plate 11 and through the tube 16. The upper end of the wire 20 is provided with an eye 21 for a purpose to be later described.

A coiled spring 22 has the lower end re-

ceived on the shoulder of the valve 17 formed by the reduced portion 18. The end of the coiled spring surrounds the reduced portion 18 as well as the wire 20. The upper end of this coiled spring engages the underside of the plate 11 and normally holds the valve within the opening as shown in Figs. 1 and 3 of the drawings.

5 A hook 23 is secured to the pipe above the platform 1 and is adapted to receive the eye 21 of the wire 20 when the valve 17 is raised.

10 From the above detailed description of the construction of my drain it is thought that the manner of using the same as well

15 as the advantages will be clearly understood. The drain is connected to the pipe 2 as shown and described and when pumping is taking place the valve 17 is received in the opening 6 as shown and is held in position

20 by the coiled spring 22. After the pumping has been stopped it is desired to drain the water from the pipe 2 so that it will not freeze and burst the pipe. To do this the ring 21 is grasped and raised upwardly

25 thereby pulling upon the wire 20 and raising the valve 17 against the tension of the coiled spring 22. The eye 21 is engaged over the hook 23 so as to hold the valve open so that the water may properly drain therefrom.

30 When one wishes to start the pump again they merely disengage the eye 21 from the hook 23 and the coiled spring 22 will force the valve 17 back in position to close the opening 6. The valve 17 is of such a length

35 that the lower end will not be drawn from the opening when raised. By making the

valve this length it will readily reseat itself when the wire is released.

40 The foregoing description and the drawings have reference to what may be considered the preferred, or approved, form of my invention. It is to be understood that I may make such changes in construction and arrangement and combination of parts, materials, dimensions, etc., as may prove expedient and fall within the scope of the appended claim.

45 Having fully described my invention what I claim as new and desire to secure by Letters Patent is:—

50 A pump drain comprising in combination with a pipe having an opening therein, a block secured to the pipe and having a transverse opening registering with the opening in the pipe and a vertical opening registering with the transverse opening, an extension formed on the block, a plate secured to the extension above the block, a valve for closing the vertical opening, a coiled spring having one end engaging the valve and the 55 opposite end engaging the plate on the extension, a tube secured to the top of the plate, a wire secured to the valve and extending through the tube, an eye formed on the upper end of the wire, and a hook secured to the pipe adapted to receive the eye.

55 In testimony whereof I affix my signature in presence of two witnesses.

ADELIA G. SHRAUGER.
